UNITED STATES PATENT OFFICE

JAMES SMITH, OF AUBURN, MASSACHUSETTS, ASSIGNOR TO JAMES SMITH & SON, OF WORCESTER, MASSACHUSETTS, A FIRM CONSISTING OF JAMES SMITH AND WILLIAM B. SMITH

ROLL ADJUSTMENT FOR WOOL COMBING MACHINES

Application filed October 20, 1930. Serial No. 489,782.

The principal object of this invention is to provide means for insuring that the adjustment of the two ends of an adjustable fluted roll will be made equally and to provide simple and convenient means for retaining the adjustment of both rolls when it has been completed.

Other objects and advantages of the invention will appear hereinafter.

Reference is to be had to the accompanying drawings, in which

Fig. 1 is an elevation of a pair of fluted rolls and means for adjusting them in accordance with this invention;

Fig. 2 is a plan of the same;

Fig. 3 is a sectional view on the line 3—3 of Fig. 2;

Fig. 4 is a plan of the adjusting means with parts removed to show the interior elements;

Fig. 5 is a sectional view on the line 5—5 of Fig. 4; and

Fig. 6 is a transverse sectional view on the line 6—6 of Fig. 1.

The invention is shown as applied to a portion of a well known type of wool combing machine in which there is a vertical fluted roll 10 on a shaft 11 mounted to turn in fixed bearings and a fluted roll 12 mounted on a shaft 13 which is located in movable bearings.

It has been customary heretofore to adjust the opposite ends of the shaft 13 independently and, as far as I am aware, there has been no means of insuring its accurate adjustment or the simultaneous adjustment of the two ends of the shaft to the same degree and also no single means for holding the adjustment of the two ends at all times. This invention is designed to accomplish these results.

The shaft 13 is mounted in two sliding blocks 14, one at the bottom and one at the top. Each of these blocks slides in a frame 15, being properly guided to move toward and from the shaft 11 radially. The two frames 15, one at the top and one at the bottom, are held together by a strut 16 positively secured in any desired way to both of these frames making a single frame. Behind

the blocks 14 are a pair of springs 17, one in each frame 15, for forcing the roller 12 toward the roller 10. Of course it is the pressure of these springs that is adjusted. The other end of each spring 17 is held in a notch in a slidable block 18, each of these blocks being held on its respective frame 15 and movable along the same and guided longitudinally on that frame and radially with respect to both rolls.

For adjusting each block 18, there is a screw 19 passing through the end of the frame 15 and through a nut 20. This nut is provided with collars 21 on both ends preventing its longitudinal motion. It is also provided with a spiral gear or worm wheel 22 fixed to the nut outside and meshing with a gear or worm 23. The two worms 23 are fixed to a shaft 24 which is vertical and may be arranged in two parts connected by a collar 25 if the distance between the frames 15 is to be changed. On the top of this shaft 24 is a head 26 having a disc 27 fixed thereon and a handle 28 eccentrically mounted by which the shaft 24 can be turned and the two screws 19 adjusted and therefore a different amount of pressure applied to both springs 17. Obviously, these parts having once been set up, the two screws 19 will be operated always equal distances and the same results secured at the top and bottom of the roll shaft 13.

The disc 27 is provided with a series of notches 29 underneath it, arranged in a circle. The top of the frame 15 is provided with an upright 30 in which is a spring-pressed pin 31 at the same distance from the center as these notches 29 and therefore adapted to slip into the notches automatically if released. This pin has a handle 32 for pulling it out of the notches to allow the adjustment to be made. Then this handle is released and the disc turned until the pin slips into one of the notches which holds the two ends of the shaft 13 fixed in adjusted position and insures that both ends will be adjusted alike. This avoids the possibility of the ends of this shaft 13 being adjusted to different degrees of pressure and the squeezing of the yarn between the two rolls.

with different pressure at the top and bottom, thus getting uneven action on the yarn.

Although I have illustrated and described only one form of the invention, I am aware of the fact that modifications can be made therein by any person skilled in the art without departing from the scope of the invention as expressed in the claims. Therefore I do not wish to be limited in this respect, but what I do claim is:—

10. 1. In a combing machine, the combination with a pair of vertical rolls, one of said rolls being mounted in fixed bearings and the other having slideable bearings at its two ends, of a pair of springs engaging the slideable bearings for forcing the two ends of the movable shaft toward the stationary shaft, two screws located beyond the ends of the springs for adjusting the pressure of the springs, two nuts through which the screws pass, a worm wheel fixed to each nut and a single shaft having two worms meshing with both worm wheels for adjusting the two screws simultaneously.
15. 2. In an adjusting device for the movable fluted roll of a combing machine, the combination with a pair of springs at opposite ends of the shaft of the movable roll adapted to supply pressure to the two ends of the shaft, a slide at the outer end of each spring, a screw for applying pressure to each slide, and two nuts located in a stationary element and having means for preventing their longitudinal motion and each meshing with one of said screws, of a worm wheel fixed to each nut, a shaft at right angles to the axes of the screws having two worms thereon meshing with said worm wheels, a disc fixed to the shaft for turning it and having notches arranged in a circle and a spring-pressed pin for holding the disc in its adjusted positions.
20. 3. In an adjusting device for the movable fluted roll of a combing machine, the combination with a pair of springs at opposite ends of the shaft of the movable roll adapted to supply pressure to the two ends of the shaft, a slide at the outer end of each spring, a screw for applying pressure to each slide, and two nuts located in a stationary element and having means for preventing their longitudinal motion and each meshing with one of said screws, of means for simultaneously turning the two nuts to advance or retract the screws equally, and retractable means for locking the turning means in adjusted position.

In testimony whereof I have hereunto affixed my signature.

JAMES SMITH.
